UNITED STATES PATENT OFFICE.

STEPHEN NICHOLS CORNWALL, OF TAMPA, FLORIDA.

ROAD OR HIGHWAY CONSTRUCTION.

1,280,964.

Specification of Letters Patent.

Patented Oct. 8, 1918.

Application filed July 16, 1918. Serial No. 245,203.

To all whom it may concern:

Be it known that I, STEPHEN N. CORNWALL, a citizen of the United States, and a resident of Tampa, in the county of Hillsborough and State of Florida, have invented 5 certain new and useful Improvements in Road or Highway Construction, of which the following is a specification.

My present invention relates generally to 10 the construction of roads or highways and particularly to an effective economical roadway construction adaptable to either one or two-way roads and my object is the provision of a lasting durable construction by 15 which cheaply constructed concrete body and surface will be presented for travel.

With these general objects in mind, my invention resides in the details to be now described in connection with the accompanying 20 drawings which form a part of this specification, and in which—

Figure 1 is a cross section through a two-way road embodying my invention,

Fig. 2 is a plan view of a portion thereof,

Fig. 3 is a cross section through a one-way road embodying the invention,

Fig. 4 is a plan view of a portion thereof,

Fig. 5 is a cross section through a slightly modified form,

Fig. 6 is an enlarged cross section through a portion of the road-way construction of Figs. 1 and 2,

Fig. 7 is a plan view of the parts shown in Fig. 6, and

Fig. 8 is a plan view of a crossing or point of intersection between roads constructed in accordance with the invention.

Referring now to these figures, my invention contemplates a road or highway in the 40 surface of which are embedded parallel longitudinal tread strips formed of concrete which may be either molded in sections apart from the roadway construction or molded *in situ*, the latter being preferable 45 and more general, although it is obvious that in either case the formation of such strips between forms, permits of a thoroughly level even surface being quickly imparted without the danger of humps and moisture 50 retaining hollows such as all roads are subjected to where they have a continuous concrete construction from side to side.

In a two-way road as seen in Figs. 1 and 2 in the accompanying drawings, the invention proposes three parallel strips 10, 11, 55 and 12, the central strip 11 of which is of

considerably greater width than the two-side strips 10 and 12, so as to coöperate in part with each of these side strips, the spacing between the several strips being in accordance with the usual gage of vehicles and are placed so as to accommodate practically all gages.

Figs. 3 and 4 differ only in the elimination of the central strip 11 of Figs. 1 and 2, Figs. 3 and 4 being a one-way road only and consisting merely of a pair of parallel spaced strips 13 and 14 of similar width, either these strips 13 and 14 of the figures last mentioned or the side strips 10 and 12 60 of Figs. 1 and 2 being variable to the extent that where they occupy practically the entire width of the highway, or in any other instance where it becomes desirable they may have a coping 15 along their edges as 65 seen in connection with the strip 16 of Fig. 5, forming a curve.

My invention also contemplates connection of the parallel roadway strips by reinforced ties 17 as seen in Figs. 6 and 7, 70 these ties being of materially reduced thickness as compared to the strips themselves, so that they do not appear in the completed roadway surface as will be seen by reference to Figs. 1 and 3. The reinforcements 75 of these lateral ties are preferably in the nature of reinforcing rods 18 extending through the ties as seen in Figs. 6 and 7 in particular, and having angular extremities 19 as seen in Fig. 6 disposed within 80 the roadway strips, the latter of which may have expansion joints 20 at suitably spaced points and of any suitable formation, connected by reinforcing rods 21 similar to the 85 reinforcing rods 18 of the lateral ties 17. 90

As a further feature thereof, my invention contemplates connection of the roadway strips at points of intersection by solid concrete platforms 22, one of which is seen in Fig. 8, either plain or reinforced, and with 100 radius curves 23 at its corners, the strips 10 and 11 and 12 leading to and joining the sides thereof so that the latter will be effectively sustained and reinforced at crossings.

In utilizing my invention it is of course 105 obvious that the tools necessary, as well as the materials, to make the strips, ties and reinforcements themselves must depend upon the nature of supplies to be had and this is obviously true also of the filling between the parallel strips and their ties in 110 order to complete a roadway of level surface

generally. It is obvious, however, that my invention provides for an effective roadway which will be considerably cheaper than the ordinary roadway, which may be much more 5 readily and quickly laid and which will be strong and durable in use.

I claim:

A roadway construction embodying parallel longitudinal strips embedded in the

roadway surface, and formed of concrete 10 having similar laterally disposed connecting ties, said strips having expansion joints in their length and reinforcing members embedded at their ends in the strips, certain of which extend through the said lateral ties 15 and others of which bridge the said expansion joints.

STEPHEN NICHOLS CORNWALL.
